UNITED STATES PATENT OFFICE.

JOHN JOSEPH HAMMEN, OF SPENCER, IOWA.

TRENCHING-MACHINE.

1,343,081.

Specification of Letters Patent.

Patented June 8, 1920.

Application filed May 9, 1919. Serial No. 295,950.

To all whom it may concern:

Be it known that I, JOHN JOSEPH HAMMEN, a citizen of the United States, residing at Spencer, in the county of Clay and 5 State of Iowa, have invented a new and useful Trenching-Machine, of which the following is a specification.

This invention has reference to trenching machines, and it relates more particularly 10 to a curb structure and parts coöperating therewith, whereby the side walls of the trench are prevented from caving in while 15 pipe or tiles are being laid in the trench, the curb being arranged to travel with the trenching machine.

In accordance with the invention, which 20 may be used in conjunction with a trenching machine or excavator of the chain or ladder type, curbs or plates are carried by the end 25 of the boom remote from the body of the excavator in trailing relation to the boom and are braced and connected so as to travel with the boom along the walls of the formed trench, thereby preventing cave-ins which 30 might be harmful to workmen following after the excavator and laying pipe in the bottom of the formed trench. The curbs or shields are so connected to the boom as to move along the trench at the bottom portion 35 thereof irrespective of the slant of the boom because of different depths of cut, while certain portions of the curb or shield structure are fixed to the boom and telescope more or less with relation to that 40 portion of the curb protecting the workmen.

In order to provide for the automatic 45 accommodation of the curb or shield, digging cutters or reamers are carried by the excavator belt or chain so as to correspondingly widen the trench and permit the easy travel of the curb along the trench, said cutters or reamers being brought into operation only in the upward travel of said belt or chain.

The invention will be best understood 50 from a consideration of the following detailed description taken in connection with the accompanying drawings forming part of this specification, with the understanding, however, that the invention is not confined to any strict conformity with the showing of the drawings, but may be changed and modified so long as such changes and modifications mark no material departure from

the salient features of the invention as expressed in the appended claims.

In the drawings:—

Figure 1 is a side elevation of a trench machine with the invention applied but 60 omitting many details of construction not pertinent to the invention.

Fig. 2 is a view of the digging end of the boom in longitudinal section and showing a portion of the curb structure carried 65 thereby.

Fig. 3 is a section on the line 3—3 of Fig. 2.

Fig. 4 is a bottom plan view of the lower or digging end of the boom showing reaming cutters thereon, and means for projecting the cutters.

Fig. 5 is a top plan view of the upper end of the boom showing means for retracting the reaming cutters.

Fig. 6 is an end view of the cutting end 75 of one of the reamers.

Referring to the drawings, there is shown a caterpillar tractor 1, boom 2, and boom supporting frame of a known type of trench 80 digger. The showing may be taken as indicative of any suitable form of trench digger, wherefore no detail description is deemed necessary. The boom carries an endless series of cutting buckets or scoops 3 85 mounted on chains 4 and the boom is supported and controlled by a derrick 5, all of which may be of usual construction. At the lower end the chains 4 pass about supporting idlers 6 which are mounted upon 90 a shaft 7 suitably journaled in the lower end of the boom.

At the lower end of the boom there are secured side plates 8 of a curb each provided with numerous longitudinal brace 95 bars 9, which may be in the form of T-bars without limitation to such particular shape, and at the rear end of each plate, that is the end remote from the boom, there is an upright T-bar 9^a. The plates 8 are braced 100 and held in spaced relation by rods 10 connected to the bars 9 and 9^a and joined intermediate of the plates 8 by turn-buckles 11, whereby the spacing of the plates may be adjusted as conditions demand. The rods 105 10 with their turn-buckles 11 also serve as bracing means which, together with the stiffening bars 9 and 9^a, effectively resist any tendency of caving in of the side walls 110 of the trench. Each plate 8 is formed at

the forward lower end with an ear 12, said ears embracing the lower end of the boom and mounted on the shaft 7 as a pivotal support so that the plates 8 may rock on 5 and be carried by the shaft.

Fast to opposite sides of the boom 2 are other plates 13, said plates being made fast to the boom so as to move therewith. These plates 13 are in telescoping relation to the 10 plates 8 and have stiffening bars 14 secured thereto. Like the plates 8, the plates 13 are joined by rods 10. The assembly of the plates 8 and 13 connected and braced as described forms a curb traveling with the 15 trench digger as it moves along the ground, the curb being located in the formed trench so that the bottom of the curb will travel along the bottom of the trench. The plates 13 are overlapped by the plates 8 and the extent of overlapping is sufficient to maintain 20 the overlapped condition despite variations in tilt of the boom and differences in angular relation of the curb members 8 and 13.

The trench formed by the buckets or 25 scoops 3 is narrower than the width of the curb, so in order to suitably form the trench to accommodate the curb, other cutters or reamers 15 are provided. These reamers travel with the series of buckets or scoops 30 3. Each reamer 15 comprises a bar 16 broadened and sharpened at one end 17, which end 17 is bent at an angle to the length of the bar 16. Extending between the chains 4 are plates 18 having clips or 35 guides 19 at the ends, each guide being traversed by a bar 16. Each plate 18 has alined slots 20 extending lengthwise of the plate on opposite sides of the center point thereof. Each bar 16 carries a roller 21 40 mounted on a pintle 22 on the bar, which pintle may be in the form of a bolt and is extended through a corresponding slot 20, and therefore the slots and pintles serve to guide the inner ends of the bars 16.

45 At the lower end portion of the beam 2 there is secured to the beam a spreader 23 which may be, as shown, a triangular or V-shaped frame in the path of the rollers 21, so that these rollers are first engaged by 50 the pointed end of the spreader, and as the chains 4 travel, the reamers have their digging edges 17 forced outwardly into engagement with the side walls of the trench close to the bottom thereof. The reamers 55 then travel along the trench in an inclined path due to the position of the boom, thereby widening the trench formed by the buckets or scoops 3. In this way the trench is made of suitably increased width to accommodate 60 the curb so that there is no undue resistance to the movement of the curb along the trench with the excavating devices.

65 The return movement of the reamers 15 cause them to pass between the plates or walls 13, and as these walls are closer to-

gether than the active projected position of the cutting edges 17, the latter must be retracted. To do this there is provided a guide frame 24 carried by the boom 2 and positioned at or near the upper end thereof 70 well out of the trench. The guide frame or closer 24 has approaching sides in the direction of travel of the rollers 21 so as to engage these rollers and move the reamer ends 17 toward each other and closer together than the spacing between the plates 13, wherefore the reamers on entering the formed trench travel between the plates 13, but as soon as they have passed the plates 13 upon their upward movement the rollers 80 21 are engaged by the spreader 23 and the reamer edges 17 are projected to engage the side walls of the trench and trim off a sufficient amount to accommodate the curb.

As the formation of the trench progresses, 85 the pipe is laid by workmen stationed within the curb between the sides thereof. Because of the curb, which is effectively braced against collapse, the workmen are always in safety, the curb being made large enough 90 to accommodate one or more workmen without interference and to permit the laying of the pipe without compelling the workmen to leave the confines of the curb. In order to avoid a burdensome structure the curb 95 may be made of a height permitting its use in a trench of average depth. If it be necessary to make the trench deeper the curb may be enlarged by adding sections to the top thereof. It will be understood, of 100 course, that the plates 8 and 13 may be made up of a plurality of individual plates riveted or otherwise secured together.

The plates 13 are fixed to the boom or parts carried thereby so as to move with the 105 boom and serve to protect the lower end of the boom from cave-ins of the side walls of the trench. The connected plates 8, constituting the main portion of the curb, provide a rigid resisting structure forming a 110 shield holding the side walls of the trench from caving in and protecting the person or persons laying the pipe. The curb made up of the plates 8 is connected to and travels with the boom, but the connection is a 115 single pivotal connection to permit changing relations between the boom and curb due to variations in the depth of the trench. Such single pivotal connection comprising the shaft 7, in the structure shown in the 120 drawings, permits the curb comprising the plates 8 to travel on and along the bottom of the trench and maintain a vertical position irrespective of variations in the angle of the boom to the bottom of the trench, 125 while the telescoping relation between the plates 13 and the plates 8 permits the variations without admitting dirt to any material extent into the curb.

130 The rods 10 are arranged in upright

series, one series being located near the front of the curb and the other series near the rear of the curb so as to leave ample working space between the rods. While any special 5 location of the reamers or cutters is not obligatory they may be conveniently located midway between the buckets or scoops 3 so as to not interfere with the scoops or be interfered with by them.

10 It has been proposed in this art to provide reamers or cutters to widen the trench cut by the buckets or scoops for the purpose of inserting planking; but in such proposed construction, the reamers or cutters were 15 pivoted so as to swing by gravity. In my construction, the reamers or cutters are forced into and out of action by means which is direct and positive in operation and does not depend upon the force of 20 gravity. It is the mechanical forcing of the reamers or cutters into and out of action which I desire to claim irrespective of the means by which this result is accomplished.

It is old in this art to employ protecting 25 plates carried by the boom to protect the same; and it is also old to employ a curb to protect the workmen, but such protecting means have always been either for the one purpose or the other, and so far as I am 30 aware, no machine has ever been constructed heretofore which combines in the same structure means for protecting both the machine and the workmen from cave-ins, said protecting means being carried by the boom 35 so as to be lifted into and out of the trench, and I therefore do not wish to be limited to the precise means described for carrying out this end.

What is claimed is:—

40 1. In a trench digging machine employing a boom carrying an endless series of buckets or scoops mounted on chains, and a shaft at the lower end of the boom provided with sprockets for the chains, the combination 45 therewith of a curb structure for traveling in a trench formed by the buckets or scoops, said structure comprising side plates connected together in spaced relation to engage the side walls of a formed trench, said 50 plates being provided at their forward lower ends with ears embracing the lower end of the boom at each side, and pivotally mounted on said shaft, and constituting the sole pivotal connection between the side plates 55 and said shaft, whereby the curb structure may maintain its position in the trench irrespective of variations in the slant of the boom.

2. In a trench digging machine having an 60 endless flexible excavating means, and auxiliary cutting means for widening the trench made by said excavating means, said auxiliary cutting means being forced into and out of cutting position by mechanism actuated by movement of said excavating means.

3. In a trench digging machine, provided with a boom, and an endless series of excavating elements carried thereby, a curb pivoted at its lower forward end to the lower end of the boom, said curb serving as a protection for workmen and maintaining its position resting on the bottom of the trench irrespective of variations of the level of the latter, said boom carrying shields on opposite sides fixed thereto, said shields closing 70 the space between the curb and the boom and providing for the protection of the boom and the parts carried thereby.

4. In a trench digging machine provided with a boom and an endless series of buckets carried thereby, a curb pivoted at its lower forward end to the lower end of the boom, said curb comprising side plates connected together in spaced relation to engage the side walls of a formed trench, whereby 80 the curb serves as a protection for workmen engaged in laying pipe in the trench and the curb will maintain its position in the bottom of the trench irrespective of variations in the relation of the boom and 85 curb, said boom carrying shields on opposite sides fixed to the boom and telescoping with the forward end of the curb.

5. In a trench digging machine provided with a boom and an endless series of buckets carried thereby, a curb pivoted at its lower forward end to the lower end of the boom, said curb comprising side plates connected together in spaced relation to engage the side walls of a formed trench, whereby 90 the curb serves as a protection for workmen engaged in laying pipe in the trench and the curb will maintain its position in the bottom of the trench irrespective of variations in the relation of the boom and curb, 95 said boom carrying shields on opposite sides fixed to the boom and telescoping with the forward end of the curb, and said curb having a series of spacing members connecting the sides of the curb near the front 100 and rear ends thereof, whereby working room is obtained within the curb between the series of spacing members.

6. In a trench digging machine provided with a boom and excavating devices carried by the boom into the trench being formed, a curb pivoted at a low point to the rear end of the boom to rock on an axis transverse of the boom, with the pivot constituting the sole connection between the boom and the curb, 110 said curb comprising side plates with longitudinal and upright stiffening bars, and spacers connected to and connecting the plates, said spacers being located in upright series near the end portions of the plates 115 whereby to provide working room between the plates.

7. In a trench digging machine provided with a boom and excavating devices carried by the boom into the trench being formed, 120

- 5 a curb pivoted at a low point to the rear end of the boom to rock on an axis transverse of the boom, with the pivot constituting the sole connection between the boom and the curb, said curb comprising side plates with longitudinal and upright stiffening bars, and spacers connected to and connecting the plates, said spacers being located in upright series near the end portions of the plates whereby to provide working room between the plates, the boom also having side plates fast to and movable with the boom during variations in its angular position and telescoping at the rear ends in the forward 10 end of the curb.
- 15 8. In a trench digging machine provided with a boom and an endless series of cutting elements carried by the boom for forming a trench, a curb connected to the lower end of the boom for traveling in the formed trench to hold the walls of the latter from caving in, and reamers carried by the boom, with the reamers and boom provided with coacting means for projecting the reamers 20 to widen the trench and for retracting the reamers before entering the trench.
- 25 9. In a trench digging machine provided with a boom and an endless series of excavating devices carried by the boom into the trench being formed, a curb at the lower end of the boom for traveling in the formed trench to prevent the caving in of the side walls thereof, a series of reamers carried by the endless series of excavating buckets 30 to widen the trench formed by the buckets so as to accommodate the curb, means at the lower end portion of the boom for projecting the reamers into active position, and means at the upper end portion of the boom 35 for retracting the reamers.
- 40 10. In a trench digging machine provided with a boom having an endless series of excavating buckets carried by the boom into the trench being formed, a curb pivotally connected to and carried by the rear end of the boom within the formed trench, shields on the boom where entering the trench and telescoping into the curb, reamers carried by the endless series of buckets and having 45 a path of travel to take them between the plates on the boom and into the curb, and means on the boom for projecting the reamers into engagement with the side walls of the trench adjacent to the lower end of the boom on the upper run of the excavating buckets and for retracting the reamers 50 before reaching the side plates on the boom while moving with the down run of the buckets.
- 55 11. In a trench digging machine having a boom with an endless series of excavating buckets including endless carrying chains therefor, with the boom directing the buckets into the trench being formed, a curb pivoted to the lower end of the boom to

move about an axis transverse of the boom, reamers carried by the chains to move with and between the buckets, and means for positively projecting the reamers into engagement with the side walls of the trench 70 and retracting them from the side walls of the trench, whereby the trench may be widened to accommodate the curb and the reamers may be retracted to a position to traverse a portion of the curb without interference therewith. 75

12. In a trench forming machine provided with a boom carrying an endless series of excavating buckets, with the boom directing the buckets into the trench, a curb 80 pivotally carried by the lower end of the boom with the axis of the pivot transverse to the boom and said pivot constituting the sole connection between the curb and the boom, side plates or shields on the boom 85 where entering the trench and telescoping into the forward end of the curb, reamers carried by the endless series of buckets to enlarge the width of the trench formed by the buckets, means located at the lower end 90 portion of the boom for projecting the reamers into engagement with the side walls of the trench, and means adjacent to the upper end portion of the boom to retract the reamers to permit them to pass between the 95 shields or plates carried by the lower end of the boom.

13. In a trench digging machine having a boom and an endless series of excavating devices carried by the boom into the trench 100 being formed, a series of reamers carried by the series of excavating devices, each reamer comprising a bar with one end broadened and sharpened and bent at an angle to the length of the bar, and a support for each 105 reamer arranged to permit lengthwise movement of the reamer on the support.

14. In a trench forming machine provided with a boom and an endless series of excavating buckets carried by the boom into the trench being formed, a series of plates carried by and extending transversely of the endless series of buckets, each plate having longitudinal slots on opposite sides of its mid-point, and guides at the extremities of 115 the plates in line with the slots, and reamers each comprising an elongated bar movable through a respective guide, said bar carrying at one end guiding means coacting with a respective slot and at the other end being 120 broadened and bent at an angle and provided with a sharpened terminal edge.

15. In a trench forming machine having a boom and an endless series of excavating buckets or cutters carried by the boom into 125 the trench being formed, plates fast to and extending crosswise of the endless series of buckets, said plates each having aligned longitudinal slots on opposite sides of its mid-point and guides at the outer ends, reamers 130

- carried by each end of each plate and extending through the guides and each reamer having a roller and a pintle therefor at the inner end, with the pintle passing through 5 a respective slot in the plate and the outer end of each reamer being bent at an angle and broadened and sharpened, a spreader at the lower end portion of the boom in the path of the rollers on the reamers to project the latter, and tracks in approaching relation and located at the upper end portion of the boom for engaging the rollers to retract the reamers.
- 10 16. In a trench forming machine having a boom and an endless series of excavating buckets or cutters carried by the boom into the trench being formed, plates fast to and extending crosswise of the endless series of buckets, reamers carried by each end of 15 each plate and each reamer having a roller, a spreader at the lower end portion of the boom in the path of the rollers on the reamers carried by the boom to enlarge the width 20 of the trench formed by the buckets so as to accommodate the shields and curb.
- 25 17. In a trench forming machine provided with a boom carrying an endless series of excavating buckets, with the boom directing the buckets into the trench, a curb 30 pivotally carried by the lower end of the boom, side plates or shields on the boom where entering the trench and telescoping into the forward end of the curb, and reamers carried by the boom to enlarge the width 35 of the trench formed by the buckets so as to accommodate the shields and curb.

In testimony that I claim the foregoing as my own I have hereto affixed my signature.

JOHN JOSEPH HAMMEN.
